UNITED STATES PATENT OFFICE.

ARTHUR R. GEOFFROY, OF NEW YORK, N. Y.

SKIRT-SUPPORTER.

SPECIFICATION forming part of Letters Patent No. 644,417, dated February 27, 1900.

Application filed August 15, 1898. Serial No. 688,588. (No model.)

To all whom it may concern:

Be it known that I, ARTHUR R. GEOFFROY, a citizen of the United States, residing in the city of New York, in the county and State of New York, have invented certain new and useful Improvements in Skirt-Supporters, &c.; and I do hereby declare that the following is a full, clear, and exact description of the same, reference being had to the accompanying drawings, making a part of this specification, in which—

Figure 1 is a face view, and Fig. 2 a transverse sectional view, of a device made according to my invention. Fig. 3 is an edge view, and Fig. 4 a face view, illustrating certain modifications included in my said invention.

This invention relates to that class of devices usually employed in connection with articles of feminine apparel and designed for temporarily supporting skirts, for holding handkerchiefs, and for various analogous purposes. It comprises certain new and useful combinations and arrangements of parts whereby is produced a simple, easily-manipulated, and cheaply-manufactured article of the class mentioned.

A is a sheet-metal part the elements of which are a hook *a*, an elastic back plate *b*, and two lateral arms *c*, one adjacent to each edge of the back plate. These elements *a b* are integral with each other, and in the process of manufacture are shaped from a single piece of sheet metal, preferably of brass or similar metal hard-rolled to afford the desired elasticity to the back plate *b*. The elasticity of the material is made available by making the back plate *b* free from the lateral arms *c* opposite their pintle-holes, so that when pressed away from these lateral arms it will yield entirely with a resilient tendency. The hook *a* may be at the front of the device, as shown in Figs. 1 and 2, or at the back thereof, as shown in Fig. 3. When desired, the form of the hook may be modified to constitute, so to speak, a "socket" adapted to receive and hold the end of a circular cord or the like, as shown in Fig. 4, without departing from my invention.

B is a lever-like plate which is pivotally connected with the extremities of the arms *c*.

This connection is made by means of studs *a'*, which are integral with the lever-plate and extend laterally from the edges thereof. These studs work in transverse holes provided in the ends of the arms *c*. Normally the lower portion *b'* of the lever-plate *B* lies approximately parallel with the back plate *b*, but its shorter portion *c'* is at an angle to the part *b'*, so that its edge bears toward the adjacent surface of the back plate, as shown in Figs. 2 and 3. This edge *a''* of the part *c'* of the lever-plate should be serrated to more effectually provide for its gripping action presently to be explained. The opposite or free extremity of the part *b'* is provided with lateral lugs *f'*, which rest against the adjacent edges of the inner portions of the arms *c* and which should extend laterally somewhat beyond the same. The parts should be so proportioned that when the lugs *f'* are thus against the arms *c* the part *c'* of the lever-plate is maintained at that angle to the back plate *b* which is the most effective in securing a firm grip upon material interposed between said back plate and said edge of the part *c'* of the lever-plate. Further, the lugs *f'* afford a convenient means whereby the lever-plate may be manipulated in applying the apparatus to use, thereby materially promoting the increased utility of the latter.

For some purposes it is desirable that the apparatus be reduced in length without shortening the hook *a*. To secure this without interfering with the swing of the lever-plate, I recess the end of the part *b'* of the latter, as shown in Fig. 1, and prolong the point of the hook *a* into said recess. By this means I preserve the effective length of the part *b'* and its full leverage upon the shorter part *c'* and at the same time retain the full length of the hook *a*.

In the use and operation of the apparatus the hook *a* may be hung upon a waist-belt or the like with the elastic back plate *b* and the lever-plate *B* pendent therefrom, so that a gathered fold of a skirt, a handkerchief, or other fabric may be thrust between the elastic back plate and the edge of the part *c'* of the lever-plate, the latter being manipulated to afford the requisite opening to receive the

fabric and then to grip the same by bringing the part *b'* of the lever-plate to its position parallel or nearly so with the back plate *b*.

When desired, the position of the device 5 may be the reverse of that just described. In other words, as in the drawings, the hook *a* made the pendent, while the back plate and lever-plate are gripped upon a fold of the garment to suspend the hook with any article 10 which may be attached thereto.

What I claim as my invention is—

1. The combination of the part, *A*, composed of the elastic back plate, the hook, and the arms, *c*, integral with each other, with 15 the lever-plate, *B*, constructed as described, pivoted to the arms, *c*, and having the inte-

gral laterally-extended lugs, *f'*, arranged to rest normally upon said arms, substantially as and for the purpose herein set forth.

2. The combination of the part, *A*, composed of the elastic back plate, the hook, and the arms, *c*, integral with each other, the lever-plate, *B*, pivoted to the arms, *c*, having the laterally-extended lugs, *f'*, arranged to rest upon the arms, *c*, and constructed with 20 the recess, at its end to receive the adjacent portion of the hook, substantially as and for the purpose herein set forth.

ARTHUR R. GEOFFROY.
